UNITED STATES PATENT OFFICE.

J. LEWIS PALLEY, OF PITTSBURGH, PENNSYLVANIA, ASSIGNOR TO PITTSBURGH TIN-WARE MANUFACTURING COMPANY, OF PITTSBURGH, PENNSYLVANIA, A CORPORATION OF PENNSYLVANIA.

COMBINATION VENTILATOR AND CARD HOLDER.

Application filed September 15, 1923. Serial No. 662,957.

To all whom it may concern:

Be it known that I, J. LEWIS PALLEY, a citizen of the United States, and a resident of Pittsburgh, in the county of Allegheny and State of Pennsylvania, have invented a new and useful Improvement in Combination Ventilators and Card Holders, of which the following is a specification.

My invention relates to ventilating devices 10 and particularly to ventilating devices for lunch boxes and kits.

One object of my invention is to provide means that shall serve to permit the ventilation of a lunch kit or similar receptacle while 15 at the same time precluding the admission of dust thereto.

Another object of my invention is to provide a ventilating device for a lunch kit or similar container whereby proper ventilation 20 may be permitted to preclude the spoiling of food therein.

Another object of my invention is to provide a ventilating device of the above indicated character that shall also serve as a 25 cardholder whereby the owner of the kit may identify it among others.

A further object of my invention is to provide a combination ventilator and cardholder of the above indicated character that 30 shall be simple and inexpensive in construction.

In practicing my invention, I provide a plurality of perforations through one of the side walls of the container or kit. I then 35 dispose a covering member of substantially saucer shape, that is also provided with a plurality of perforations so as to cause the apertures in the covering member to be offset from those in the side wall of the kit. The 40 covering member thus permits free ventilation while at the same time precluding the direct admission of dust into the interior of the kit.

A portion of the covering member is depressed and two slots provided at the respective ends of the depression to receive a card or other identifying means whereby the owner of the lunch kit may identify the same.

Figure 1 of the accompanying drawings is 50 an end elevational view of a lunch kit illustrating the disposition of the ventilating device.

Figure 2 is a sectional view of the venti-

lating device taken along the vertical line 55 II-II, and

Figure 3 is a sectional view of the ventilating device taken along the horizontal line III-III.

As illustrated in the accompanying drawings, a portable receptacle such as a lunch kit 1 is provided with a plurality of ventilating apertures 2 through the end wall 3 of the kit. A covering member or ventilating device 4 is so disposed as to enclose and cover 65 the apertures 2 in the wall of the kit 1.

The ventilating device 4 constitutes a member of substantially saucer shape and is provided with a plurality of apertures 5, a depressed portion 6 and two slots 7 and 8 70 at the respective ends of the depressed portion 6. The slots 7 and 8 are adapted to receive a card or other identifying means whereby the owner may identify his kit 75 when placed among many others.

The ventilating device 4 is secured to the box by means of a rivet 9 or other suitable fastening means to preclude relative movement therebetween and is so disposed, when secured to the kit, that the apertures 5 in the 80 ventilating device are located diametrically opposite to the apertures 2 extending through the end wall 3 of the kit.

The ventilating device also embodies an enclosing portion 10 which constitutes the 85 perimeter of the device 4, and a ventilating portion or pocket 11 which constitutes a ventilating passage or chamber through which the air may circulate between the apertures in the kit and those in the ventilating device 4.

By means of a covering member or ventilating device 4 of the construction that is illustrated, and disposed in non-registering position, as indicated, the kit may be well 95 ventilated and the direct admission of dust or other particles thereto may be precluded.

My invention is not limited to the specific structure that is illustrated since various modifications may be made therein without 100 departing from the spirit and scope of the invention as set forth in the appended claims.

I claim as my invention:

1. A ventilator and card holder for a 105 lunch box comprising a stamping of saucer shape adapted to be secured to the box by a rivet through its center, the stamping being

provided with a centrally depressed rectangular portion symmetrically disposed about the center and severed from the stamping at two opposite sides to provide openings for accommodating an identification card, and being further provided with openings in the non-depressed portion through which air may pass.

2. A ventilator and card holder for a lunch box comprising a single stamping of substantially saucer shape having a central depressed rectangular portion severed from the stamping at two ends thereof to provide openings for accomodating an identification card, the disposition of the card to be such that it will be lower than the outer surface of the remainder of the stamping.

3. A combination ventilator and card holder for use with a lunch kit, consisting of a single stamping of substantially saucer shape having a central portion displaced to substantially the plane of the rim of the stamping so that such portion and the rim

will closely engage a surface of the kit to permit the stamping to be secured thereto by a single rivet through its center, the depressed portion being severed from the remainder of the stamping at two places to permit the insertion of an identifying card, and the non-depressed portion being provided with openings to permit air to pass for ventilation of the kit.

4. A ventilating device for a portable receptacle, comprising an element provided with an enclosing portion for engaging a surface of the receptacle at the perimeter of the element, a depressed central portion engaging the same surface to permit secural thereto, and a pocket portion between the depressed central portion and the perimeter to serve as a passage for the circulating air.

In testimony whereof, I have hereunto subscribed my name this 28th day of August, 1923.

J. LEWIS PALLEY.
